UNITED STATES PATENT OFFICE

141,236

DESIGN FOR A FLORAL PIECE

Edward R. French, Ocean City, N. J.

Application July 8, 1943, Serial No. 110,629

Term of patent 14 years

(Cl. D29—1)

To all whom it may concern:

Be it known that I, Edward R. French, a citizen of the United States, residing at Ocean City, in the county of Cape May and State of New Jersey, have invented a new, original, and ornamental Design for a Floral Piece, of which the following is a specification, reference being had to the accompanying drawing, forming part thereof, in which

Figure 1 is a perspective view of a floral piece showing my new design, and

Figure 2 is a similar perspective view of the

floral piece but with a portion thereof broken away to show the supporting structure.

The characteristic feature of my design resides in a floral piece of the configuration shown having contrasting colored flowers arranged transversely of the supporting member in a series of parallel stripes of varying width and color substantially as shown.

I claim:

The ornamental design for a floral piece, as shown and described.

EDWARD R. FRENCH.
